UNITED STATES PATENT OFFICE.

OTIS H. OAKLEY, OF MINNEAPOLIS, MINNESOTA, ASSIGNOR OF ONE-FOURTH TO INA M. ROSS AND ONE-FOURTH TO ARTHUR B. ROSS, BOTH OF HENNEPIN COUNTY, MINNESOTA.

MEANS FOR EMBALMING THE DEAD.

No Drawing.

Application filed June 15, 1922. Serial No. 568,621.

To all whom it may concern:

Be it known that I, OTIS H. OAKLEY, a citizen of the United States, residing at Minneapolis, in the county of Hennepin and State of Minnesota, have invented new and useful Improvements in Means for Embalming the Dead, of which the following is a specification.

The object of my invention is to provide improved means for embalming the dead.

Methods of embalming now in common use make it necessary to inject the fluid employed either into the arterial system or into the cavities of the body or both, and this, of course, requires a mutilation of the body.

By the use of my improved fluid and method I have found that in most instances satisfactory results may be obtained without any cutting or puncturing of the corpse whatever, and that, in exceptional cases where an injection may be desirable, the amount of mutilation and volume of the injection is greatly decreased.

The solution which I use is composed of boric acid, nitrate of soda, chlorate of potassium, chloral hydrate and formaldehyde combined in the presence of alcohol, and this fluid possesses the remarkable quality of being quickly absorbed by the flesh and penetrating to the bone. The formaldehyde is used in my solution because it is required by the laws of a number of States, but it is not essential to the efficiency of my process.

I have found that the best results are secured by combining these ingredients in substantially the following proportions: boric acid 12 ounces, nitrate of soda 12 ounces, chlorate of potassium 12 ounces, chloral hydrate 8 ounces, formaldehyde 5 ounces and alcohol 32 ounces. After allowing this solution to stand for about an hour I dilute it with 4½ gallons of water after which the

fluid is ready for use. In this condition it will neither freeze nor deteriorate. In all cases where the corpse is in normal condition efficient embalming is secured by merely applying the liquid to the outer surfaces of the body with a brush or sponge. I prefer the use of a brush as the application can be made more evenly therewith. In cases of purging and of loosening of the flesh from the bones, I have found that four or five applications, in the manner described, to the surfaces of the body will restore it to normal condition. Bleaching and the disappearance of congested spots occurs within forty minutes after the application and all disagreeable odors are destroyed promptly.

Having described my invention what I claim as new and desire to protect by Letters Patent is:

1. The method of embalming bodies which consists in applying to the outer surface thereof a solution compounded of boric acid, nitrate of soda, chlorate of potassium and chloral hydrate in the presence of alcohol.

2. The method of embalming which consists of combining boric acid, nitrate of soda, chlorate of potassium and chloral hydrate in the presence of alcohol and permitting the same to stand, then diluting the solution with water and applying the same to the outer surfaces of the body to be treated.

3. An embalming fluid consisting of a dilute solution compounded of the following named ingredients in approximately the proportion named, i. e. boric acid, 12 ounces; nitrate of soda, 12 ounces; chlorate of potassium, 12 ounces; alcohol, 32 ounces; chloral hydrate, 8 ounces.

In testimony whereof, I have hereunto signed my name to this specification.

OTIS H. OAKLEY.
